(57) **CLAIM**

The ornamental design for a storage device, storage device enclosure, and support for a storage device enclosure, as shown and described.

DESCRIPTION

FIG. 1 is a perspective view showing one embodiment of our design, which embodiment is also shown in FIGS. 2–6;

FIG. 2 is a front view;

FIG. 3 is a rear view;

FIG. 4 is a bottom view;

FIG. 5 is a top view; and

FIG. 6 is a side view;

FIG. 7 is a perspective view showing another embodiment of our design, which embodiment is also shown in FIGS. 8–12;

FIG. 8 is a front view;

FIG. 9 is a rear view;

FIG. 10 is a top view;

FIG. 11 is a side view; and,

FIG. 12 is a bottom view.

(73) Assignee: **Iomega Corporation**, Roy, UT (US)

(**) Term: **14 Years**

(21) Appl. No.: **29/141,898**

(22) Filed: **May 14, 2001**
